(57) **CLAIM**

The ornamental design for a multi-device dash mount for vehicles, as shown and described.

DESCRIPTION

FIG. 1 is a perspective view of a multi-device dash mount for vehicles showing our new design in a first configuration. FIG. 2 is a side view thereof.

FIG. 3 is a top view thereof.

FIG. 4 is a front view thereof.

FIG. 5 is a bottom view thereof.

FIG. 6 is a rear view thereof.

FIG. 7 is another perspective view thereof, shown with a GPS unit mounted thereto.

FIG. 8 is a perspective view of the multi-device dash mount for vehicles showing our new design in a second configuration.

FIG. 9 is a side view thereof.

FIG. 10 is a top view thereof.

FIG. 11 is a front view thereof.

FIG. 12 is a bottom view thereof.

FIG. 13 is a rear view thereof; and,

FIG. 14 is another perspective view thereof, shown with both a GPS unit and camera unit mounted thereto.

The broken lines illustrate a GPS unit and a camera unit that may be mounted to the multi-device dash mount, which GPS unit and camera unit form no part of the claimed design.
